UNITED STATES PATENT OFFICE.

STANLEY W. LAW, OF ST. PAUL, MINNESOTA.

VARIABLE-RESISTANCE UNIT.

1,408,953.

Specification of Letters Patent.

Patented Mar. 7, 1922.

Application filed January 17, 1919, Serial No. 271,711. Renewed July 11, 1921. Serial No. 483,949.

To all whom it may concern:

Be it known that I, STANLEY W. LAW, a citizen of the United States, resident of St. Paul, county of Ramsey, State of Minnesota, have invented certain new and useful Improvements in Variable-Resistance Units, of which the following is a specification.

The object of my invention is to improve the resistance block or unit shown and described in Letters Patent of the United States, No. 1,142,586, issued to me June 8, 1915. In the use of this invention I have discovered that a bolt or discharge of lightning has a tendency to jump from the edge or corner of the conducting plate to the resistance wire and burn out the unit and my present invention obviates this difficulty by so mounting the plate that there will be less distance between it and the adjacent terminal than between the plate and the resistance coil. The result is the high tension electric discharge will jump the narrow gap to the terminal rather than the wider gap to the resistance coil.

25 The invention consists generally in various constructions and combinations, all as hereinafter described and particularly pointed out in the claims.

In the accompanying drawings forming part of this specification,

Figure 1 is a plan view of a resistance unit embodying my invention,

Figure 2 is a longitudinal sectional view of the same,

35 Figure 3 is a sectional view on the line 3—3 of Figure 2.

In the drawing, 2 represents a block of suitable insulating material, preferably porcelain, wherein the terminals 3 and 4 are mounted in the usual way. Between these terminals the block is provided with a spiral groove 5. A resistance wire 6 is attached at its end to the terminals 3 and 4 in the usual way and is coiled in the groove 5 which

45 around the resistance wire is filled with a suitable insulating material 7 so that the wire is thoroughly concealed and protected thereby. On the upper side of the block the resistance wire is provided with a series of 50 metallic contacts 8 formed in any suitable way, preferably by dropping solder or like material on the coil. These contact surfaces are arranged preferably in rows, as indicated in Figure 1, running lengthwise of the

block, the contacts of one row being in 55 staggered relation to those of the other row and there being as many contact surfaces as there are sections of the groove in the top of the block, although in Figure 1 I have shown one groove at the right hand end of 60 the block with the contact surface omitted from the wire section in that groove. These contact surfaces project up through the insulating material 7 and are exposed on the upper surface of the block and the wire 65 closes the circuit between the terminals through these contacting surfaces. For the purpose of varying the effective length of the resistance wire through which the current is compelled to pass or in effect short-circuiting the resistance, I provide a plate 9 mounted on one of the terminals 3 and having an offset 10 formed therein near the terminal for the purpose of raising that portion of the plate which overhangs the 70 resistance wire a considerable distance therefrom to form a wider gap at this point than shown in my patent above referred to, and at the same time have the end of the plate that is mounted on the terminal the same 75 distance from the top of the block. This wide air gap between the plate and the coil reduces, of course, the tendency of an electric discharge to jump from the plate to the wire. The plate is provided with a series of 80 holes 11 in which a contacting screw 12 is tapped and secured by suitable means, such as a lock nut 13, the number of holes in the plate corresponding to the number of contact surfaces on the wire and by moving the 85 contact screw back and forth in the holes I am able to increase or decrease the degree of resistance in the coil, reducing or increasing the number of loops in the wire through which the current is compelled to 90 pass in flowing from one terminal to the other.

The end 14 of the plate 9 instead of being cut square across and terminating a considerable distance from the terminal as in 100 my former patent, is made tapered and extends to a point where there is only a narrow gap between it and the terminal, so that if a bolt of lightning enters the instrument, it will follow the shortest air gap and 105 jump from the point of the end 14 to the terminal rather than from the plate to the resistance wire and this direction of flow of

the electric discharge is made all the more probable by the tapered form of the end of the plate; that is, the corners are cut away which in my former patent overhung the 5 resistance coil and afforded a convenient path for the electric discharge to jump to the coil from the end of the plate.

These two features—the forming of the conductor plate to raise it above the resistance coil and the tapered end of the plate— 10 form the subject matter of my present invention.

I prefer to provide a soft iron core 15 molded in the block 2 and encircled by the convolutions of the coil. This core, which is preferably in the form of a solid iron rod, will greatly increase the impedance of the coil to the passage of a lightning discharge and thereby increase the efficiency of the 20 device for the purpose designed.

I claim as my invention:

1. A resistance unit comprising an insulating block and terminals mounted thereon, a resistance wire in circuit with said terminals and coiled around said block, a contact plate in circuit with one of said terminals and overhanging the coils of said wire, means adjustably mounted on said contact plate for contacting with the convolutions 25 of said wire and said plate having a tapered end extending to a point near the other terminal and having a narrower air gap between it and said terminal than between said plate and the adjacent wire convolutions.

3. A resistance unit comprising an insulating block and terminals mounted thereon, a resistance wire in circuit with said terminals and coiled around said block, a contact plate in circuit with one of said terminals 40 and overhanging the coils of said wire, means adjustably mounted on said contact plate for contacting with the convolutions of said wire and said plate having one end extending to a point near the other terminal 45 and having a narrower air gap between it and said terminal than between said plate and the adjacent wire convolution.

3. A resistance unit comprising an insulating block and terminals mounted thereon, 50 said block having a spiral groove formed therein between said terminals, a resistance wire in circuit with said terminals and coiled around said block in said groove, and insulating material wherein said wire is embedded in said groove, the convolutions of said wire having contacting surfaces formed thereon exposed through said insulating material, a contact plate in circuit with one of said terminals and overhanging said contacting surfaces and having a wide gap between them and a circuit closing device 60 mounted on said plate and movable thereon for engaging said contacting surfaces.

4. A resistance unit comprising an insulating block and terminals mounted thereon,

a resistance wire in circuit with said terminals and coiled around said block, a contact plate in circuit with one of said terminals and overhanging the convolutions of said resistance wire and spaced therefrom, said 70 plate having an offset therein adjacent said terminal for increasing the width of the air gap between said plate and said wire convolutions, the end of said plate being adjacent the other terminal to provide a narrower air gap between them than between said plate and wire convolutions, said wire having contacting surfaces formed thereon and a circuit closer mounted on said contact plate and movable thereon for engaging said 80 contacting surfaces.

5. A resistance unit comprising an insulating block and terminals mounted thereon, a resistance wire in circuit with said terminals and coiled on said block, a contact plate 85 in circuit with one of said terminals and overhanging the coils of said wire and spaced therefrom, there being a narrower air gap formed between said contact plate and the other terminal than between said 90 contact plate and the convolutions of said coil, for the purpose specified.

6. A resistance unit comprising an insulating block and terminals mounted thereon, a resistance wire in circuit with said terminals and coiled on said block, a contact plate in circuit with one of said terminals and overhanging the coils of said wire and spaced therefrom, there being a narrower air 95 gap formed between said contact plate and the other terminal than between said contact plate and the convolutions of said coil, for the purpose specified. 100

7. A resistance unit comprising an insulating block and terminals mounted thereon, a resistance wire in circuit with said terminals and coiled around said block, a contact plate in circuit with one of said terminals 110 and overhanging the coils of said wire, means mounted on said contact plate for contacting with the convolutions of said wire and said plate having one end extending to a point near the other terminal and having a narrower air gap between it and said terminal than between said plate and the adjacent wire convolution.

8. A resistance unit comprising an insulating block and terminals mounted thereon, a resistance wire in circuit with said terminals and coiled around said block, means for establishing a circuit through one of said terminals and the convolutions of said coil, said means being mounted to direct a lightning discharge away from said coil and through the other terminal. 120

9. A resistance unit comprising an insulating block and terminals mounted thereon, a resistance wire in circuit with said termi- 125

nals and coiled on said block, means for short circuiting said resistance wire through one of said terminals and directing a lightning discharge into the other terminal.

5 10. A resistance unit comprising an insulating block and terminals mounted thereon, a resistance wire in circuit with said termi-

nals and coiled on said block, and means for diverting a lightning discharge from said resistance wire to said terminals.

10 In witness whereof, I have hereunto set my hand this 4th day of September, 1918.

STANLEY W. LAW.
